UNITED STATES PATENT OFFICE.

ERNST F. STECK, OF CHICAGO, ILLINOIS, ASSIGNOR TO THE FIRE EXTINGUISHER MANUFACTURING COMPANY.

LANTERN.

SPECIFICATION forming part of Letters Patent No. 349,618, dated September 21, 1886.

Application filed March 19, 1886. Serial No. 195,831. (No model.)

To all whom it may concern:

Be it known that I, ERNST F. STECK, a citizen of the United States, residing at Chicago, in the county of Cook and State of Illinois, 5 have invented certain new and useful Improvements in Lanterns, of which the following is a specification, reference being had therein to the accompanying drawings.

This invention relates to that class of lanterns in which the air is supplied to the flame through tubes which communicate with an air-chamber below the burner and extend upwardly on the outside of the globe to or above the level at which the products of combustion or 15 the heated air escape from the lantern.

The object of this invention is the construction of a simple and compact lantern of good appearance, particularly adapted for use by fire-departments, and in connection with fire-department apparatus, in which the flame is not extinguished when the lantern is exposed to the wind, or is violently agitated or is struck by water from a hose.

My invention consists in the peculiar construction of the lantern, as will be hereinafter fully set forth in connection with the drawings, in which—

Figure 1 represents one half of the lantern in elevation and one half in section. Fig. 2 is a 30 top view of the same lantern, constructed in accordance with my invention. Fig. 3 is a bottom view of the casting forming the upper end of the air-feeding tubes. Fig. 4 is a top view of the oil-cup, showing in horizontal section the air-chamber resting thereon and a portion of the air-feeding tubes. Figs. 5 and 6 represent, 35 respectively, in side view and top view the disk through which the air passes before entering the air-feeding tubes. Figs. 7 and 8 represent, respectively, in side view and top view the combined disk and cap used to assist in protecting the air-passages in the top of the lantern. Figs. 9 and 10 represent, respectively, in side and top view the lower disk or 45 holder for the upper end of the glass globe.

In said drawings, *a* represents the oil-cup carrying the wick-tube *b* and burner-cone *c*, and upon the shoulder of said cone rests the perforated plate *g*, supporting the lower end

of the glass globe *d*. Surrounding the wick-tube is the air-chamber *e*, into which air is admitted through the two tubes *g*, arranged upon diametrically opposite sides of said air-chamber. A small perforation, *f*, is made also in the side of the air-chamber to admit therein a small quantity of air if the supply through the tubes should be insufficient. The tubes *g* extend upward on the outside of the globe to a point above the level at which the products of combustion are discharged, and enter the ends of a hollow casting, *h*, to the central portion of which is attached the upper hemispherical cap, *i*, having its lower edge flanged out and forming the disk *i*², to prevent the entrance of falling water into the lantern. A short distance below the combined cap and disk *i*² is secured another nearly similar combined cap and disk, *l*. The fastenings between the two consist of four small bolts, *n*, passing through the disk *i*² *l* at substantially diametrically opposite points. A sleeve, *n*², is placed upon each of the bolts *n*, to keep the disks at proper distances apart to form an annular passage for the admission of air into the bottom entrance to the casting *h*, and into said annular passage there is placed a perforated disk, *k*, to moderate and equalize the ascending current of air. This disk *k* has its inner flange riveted to the convex surface of the cap *l*, and the latter has a series of small perforations, *l*², to permit a portion of the heated gases from the interior of the globe to ascend under the upper cap, *i*. The upper end of the glass globe is retained in a proper central position by means of a ring, *m*, having flanged base or disk *m*², through which passes as guides the lower portion of the bolts *n*. 50 55 60 65 70 75 80 85 8c

To raise and lower the ring *m* it has in its upper portion a diametrical bail or transverse bar, *m*¹, centrally perforated and screw-tapped 90 to receive the vertical screw *o*. The upper end of this screw is diametrically reduced and passes through the walls of the casting *h*, and on said reduced portion is riveted to the thumb-nut *p*, so as to form upon it a collar under 95 and above the casting, which while permitting the screw *o* to be revolved, prevents any end motion of the same. The bottom of the cast-

ing h has a large opening, h' , to permit the free passage of the screw, and the cap l has also a large central opening, l' , for the same purpose. Two or more wires, r , are made to encircle the tubes g opposite the middle portion of the globe d , to protect the latter against concussion. Projecting from the top of the casting h are perforated lugs h^2 , to receive the looped ends of the wire handle s .

10. The oil-cup a is of such size as to contain a supply of oil to burn about thirty hours.

The lantern is lighted by inserting toward the wick a lighted match in the largest hole made in the perforated plate g ; but when the 15 wick is to be trimmed or the globe cleaned, by slackening up the screw o , which elevates the ring m from on top of the globe, and after the wick has been trimmed and the parts cleaned the globe is then replaced and the ring m forced 20 down upon it by the central screw.

The heated gases and products of combustion ascending in the globe pass out mostly between the disks l and m^2 ; but a small portion also passes upward through the perforations l' in the disk l and through the perforation in the disk k , whereby they become mixed with the fresh air entering between the disks i^2 and l , and enter the curved passages in the casting h , leading to the tubes g , and downward through 25 them to the air-chamber e surrounding the wick-tube.

By the arrangement of the caps i l m and their horizontal flanges or disks i^2 l m^2 , the upper end of the globe is well protected against 30 a stream of water that may issue from a hose, so that the lantern cannot be extinguished thereby.

Having now fully described my invention, I claim—

40. 1. A lantern provided with side air-tubes,

connected with an air-chamber around the burner, and with a tubular casting and an upper cap having its lower edge flanged outwardly, and under said cap two other caps having their lower edge flanged outwardly, and a 45 screw passing through the caps whereby the lower cap is vertically adjustable, in combination with a glass globe entering and fitting within the lower cap, whereby the admission of water projected against said globe is prevented, substantially as and for the purpose described.

2. In combination with the oil-cup, burner, glass globe, and the side air-tubes of a lantern, the casting receiving their upper ends and the 55 hemispherical cap secured to said casting and provided with an outwardly-projecting disk at its lower edge, the combined cap and disk l , and bolts n , uniting the disks of both caps, substantially as and for the purpose described. 60

3. In combination with the oil-cup, burner, glass globe, and the side air-tubes of a lantern, the casting receiving their upper ends and the two caps with their pendent guide-bolts, the globe receiving disk having perforation for 65 the passage of said guide-bolt, substantially as and for the purpose described.

4. The combination of the oil-cup, burner, glass globe, and the side air-tubes of a lantern, the casting receiving their upper ends, the two 70 caps retained apart by bolts passing through their outwardly-projecting disks, and the perforated disk k between the caps, substantially as and for the purpose described.

In testimony whereof I affix my signature in 75 presence of two witnesses.

ERNST F. STECK.
